ELECTRIC MOTOR OPERATED CENTRIFUGAL PUMP

Elmer C. Slaughter, Piqua, Ohio

Application November 16, 1948, Serial No. 149,671

Term of patent 14 years

(Cl. D65—1)

To all whom it may concern:

Be it known that I, Elmer C. Slaughter, a citizen of the United States, residing at Piqua, Miami County, Ohio, have invented a new, original, and ornamental Design for an Electric Motor Operated Centrifugal Pump, of which the following is a specification, reference being had to the accompanying drawings, forming a part thereof, in which Fig. 1 is a perspective view of an electric motor operated centrifugal pump embodying my new design;

Fig. 2 is a top plan view thereof;

Fig. 3 is a side view thereof; and

Fig. 4 is another side view thereof with the pump turned ninety degrees from the position shown in Fig. 3.

I claim:

The ornamental design for an electric motor operated centrifugal pump, substantially as shown.

ELMER C. SLAUGHTER.
